BANK MULTIPLE CONTACT STRUCTURE FOR TELEPHONE SWITCHING MECHANISMS

Willy Lohs, Berlin-Siemensstadt, Friedrich Sommer, Berlin-Nikolassee, and Walter Breustedt, Berlin-Charlottenburg, Germany, assignors to Siemens & Halske Aktiengesellschaft, Munich, Germany, a corporation of Germany

Application February 28, 1952, Serial No. 274,014

13 Claims. (Cl. 179—27.5)

This invention relates to a bank contact multiple structure for switches used in signalling systems, especially automatic telephone systems, and is particularly concerned with a bank contact multiple structure comprising sets of continuous flat and narrow bandlike conductors bent or folded about elongated platelike insulating mounting or holder members to form flat spirals which extend in back of several switches, the conductors forming at the bending or folding edges of the platelike insulating holder members bare contact points in fixed intimate engagement with said edges, such contact points constituting bank contacts of the corresponding switches. A structure of this type is disclosed in copending application Ser. No. 273,847, filed February 28, 1952.

The platelike insulating holder members are made of synthetic insulating material and are disposed end to end. The insulating material used for these holder members is chosen for its good dielectric property, easy workability, elasticity and resistance against breakage. The disadvantage of such material is that it is subject to dimensional changes, due to the effect of temperature and moisture. Expansion and contraction may cause warping of the holder members and may thus produce shunts between individual conductors or positional changes in the bank contacts formed thereby.

The object of the invention is to provide a bank contact multiple structure of the above indicated type in which changes in the platelike insulating holder members which are due to temperature or moisture fluctuations, are so controlled that they do not affect the proper operation of the associated switches.

This object is realized by the provision of means for anchoring on the frame of each switch the inner portions of the insulating holder members corresponding thereto, such portions facing the switch axis and carrying the bank contacts formed by the conductors supported thereby, the anchoring being such that dimensional alterations are at the inner contact-carrying portions or edges suppressed so that such alterations can be become effective only in the opposite direction radially outwardly away from the bank contacts where they cannot do any harm.

The invention recognizes the fact that the angular spacing between the insulating holder members or plates increases radially rearwardly toward the cable side of the corresponding switches, due to the radial positioning of the holder members relative to the switch axes, so that expansion and contraction can be absorbed rearwardly without harm to the inner bank contact-carrying portions thereof. Dimensional and positional changes in the bank contacts, which are detrimental whether they are directed axially or radially, are thus avoided, and the proper angular spacing between the individual bank contacts is assured and maintained.

The invention meets the requirements by constructional objects and features which cooperate toward the common desired end. One of these objects is to provide a platelike insulating holder structure for securing

2

the conductors, comprising a main plate and one or more auxiliary plates, and anchoring the bandlike narrow bank multiple conductors at the inner bank contact portions thereof on the main plate, while the rear or outer portions of such conductors are anchored on the auxiliary plate or plates, the bandlike conductors extending between these plates.

The platelike insulating holders can in such a structure undergo certain positional changes without any danger of causing shunts between the bare bandlike conductors.

In order to distribute dimensional changes in the platelike insulating holder members axially of the respectively associated switch and to distribute manufacturing tolerances from a predetermined point in both directions, the invention provides mounting means for securing or anchoring the main plates in a median plane of the bank multiple, such mounting means engaging a notch or recess provided on the main plates at the bank contact side thereof. The radial anchoring or securing of the main plates is accomplished by ringlike members which are carried on the switch frame and project into notches or recesses on the main plates at the ends thereof. These recesses are deep enough to absorb expansion of the main plates axially of the switch.

Segmentlike members having serrated edges are provided for determining the angular spacing between the main plates. These segmentlike members are fixed on the switch frame in predetermined position, preferably at levels coinciding with the private bank contacts thereof.

In order to secure the main plates of the holders associated with a switch in correct angular relationship at the rearward edges facing the wiring cables, there is provided in a median plane of the corresponding switch a comblike dividing member which engages cutouts about centrally of the main plates, such cutouts being formed so as to permit expansion and contraction of the main plates in radial direction at the rear or cable wiring side thereof.

The structure and arrangement of the various mounting and anchoring means secures the insulating main plates of the holders at the inside thereof which faces the switch axis (bank contact side) in such a manner that expansion or contraction of such plates cannot become detrimental to the bank contacts, remaining within permissible limits, and that the angular spacing between the individual insulating plates of the holders at the rearward ends facing the wiring cables also remains within permissible limits. The positions of the bank contacts are definitely determined by the anchoring and mounting means of the invention. The proper positions of the switch arms or wipers relative to the bank contacts are determined by fitting means on the switch casing for mounting thereon the rotary parts of the mechanism together with the drive means therefor. These fitting means comprise suitable aligning pins and coaxing bushings which are disposed in a median plane of the switch, so that manufacturing tolerances can become effective in two directions.

In accordance with another feature of the invention, both legs of each narrow bandlike conductor which is wound about the insulating holder plates are fixed in proper position relative to one another. This is done by clamping each conductor at its folding or bending edge forming the inwardly positioned bank contacts on the corresponding main plates and by also anchoring the conductor on the auxiliary holder plates which are disposed rearwardly at the side facing the wiring cables.

This additional securing of the positions of the bandlike conductors upon the insulating holder plates renders the advantage and possibility of permitting, if needed, separation or cutting of the multiple at the wiring cable

side, since the bandlike conductors are separately fastened to the auxiliary holder plates. The bare bandlike conductors are for this purpose carried beyond the associated auxiliary insulating holder plates at the side facing the wiring cables and are folded so as to permit electrical separation of each individual conductor by a simple cutting and outward bending thereof. The mechanical continuity of the multiple conductor band is nevertheless maintained, because the conductors are fixedly held and properly spaced on the auxiliary insulating holder plates which are made in the form of narrow strips.

The foregoing and additional features and objects will become apparent from a description of an embodiment, which will presently be rendered with reference to the drawings.

In these drawings,

Fig. 1 shows in diagrammatic perspective representation a switch housing and parts of the bank contact multiple provided therein;

Fig. 2 is a diagrammatic sectional view taken along the switch axis along line A—B of Fig. 1;

Fig. 3 indicates, on an enlarged scale, a section through a main holder plate taken approximately along line F—G of Fig. 2; and

Fig. 4 is a similar sectional view through an auxiliary holder plate taken approximately along the line C—D of Fig. 2.

The bandlike conductors 1 are punched from flat metallic stock and are suitably machined to assume the form shown in Fig. 2. The insulating holder plates 2, 25, 25', which are made of synthetic insulating material, hard paper or other suitable dielectric, are assembled with the sets of conductors, while the latter are still held together by a waste strip that remained from the punching operation and are fixedly connected with the individual conductors, whereupon the waste parts that remained from the punching operation are removed.

The insulating holder extending over the space occupied by one switch comprises a main plate 2 and two auxiliary plates 25, 25', the latter being narrow strips or barlike members. Holes 3 are punched in the main plate 2 for the purpose of fastening the corresponding bare bandlike conductors 1 by means of ears formed on the conductors 1, which are disposed in these holes and bend over to secure the corresponding conductors in place. Both legs of each conductor 1 are in this manner anchored on the main plate at the bending edge thereof which forms the bank contact.

The fastening of the bandlike conductors at the auxiliary holder plates 25, 25' is accomplished by ears 26, 26' formed thereby, as shown in Fig. 4.

The bandlike conductors extend over several switches. They form the multiple cable for the associated switches and are mounted on the individual switch frames after assembly with the insulating holder plates. Mounting means are provided to secure the insulating holder plates in their proper positions. The main plate 2 is for this purpose provided with a number of cutouts for coaction with the mounting means. For fixing the insulating main plates 2 axially of the switch, there is provided an arcuate mounting member 5 which is mounted in the median plane of the die-cast switch frame 7 on shelflike frame portions 6. The surfaces of these portions, shown in Fig. 1 only on one switch side, are accurately machined so as to definitely determine the position of the arcuate mounting member 5. As is apparent from Fig. 2, the arcuate mounting member 5 engages a cutout 8 in each main plate 2. The depth of the cutout permits shifting of the main plates in radial direction. The arcuate mounting member 5 therefore serves only for determining the position of the holder main plates 2 in axial direction. Expansion and contraction of the main plates, if they occur, are by the anchoring centrally thereof by the mounting member 5 equally distributed to both sides.

Segmental members 9—13 are provided for determining the angular spacing between the main insulating

holder plates 2 at the inner bank contact sides or edges thereof. These segmental members are likewise secured on portions of the frame corresponding to the shelflike portions 6 for the arcuate mounting member 5. The segmental members are serrated, forming notches for receiving the various insulating holder plates at the inner edges thereof, and engage cutouts 14 in the insulating plates 2. These cutouts are again formed in such a manner that they permit some displacement of the insulating holder plates axially of the switch. The segmental member 11 is fastened on the shelflike frame portions 6 together with the arcuate mounting member 5.

The segmental anchoring members 9—13 thus determine the angular positions of the main insulating holder plates 2. However radial displacement of the holder plates 2 at the bank contact side of the switch (the bank contacts being indicated at 15) must be prevented and there are for this purpose provided ringlike members 17, 17' at the opposite ends of the main insulating holder plates 2 engaging recesses 16, 16' therein, the anchoring being effected by the rims 18 of these ringlike members. The rim is shown broken away in Fig. 1. The rims of the ringlike members are pointed, as indicated in Fig. 1, in order to facilitate the assembly with the other parts of the structure. The height of the rims 18 permits displacement of the insulating holder plates 2 axially of the switch but these plates are held against radial displacement.

The angular spacing between the individual insulating holder plates 2 is not only secured by the segmental members 9—13, which are on the inner or bank contact side of the structure, but also by the segmental member 19 which is disposed at the rear of the main plates 2 and is screw-connected with the frame parts in a median plane thereof. This latter segmental member 19 thus serves to maintain the angular spacing between the insulating holder plates 2 at the rearward edges thereof which face the wiring cables. Notches are provided in the segmental member 19 corresponding in number to the number of insulating holder plates 2.

The insulating holder plates 2 must be held in accurate position relative to the switch axis by the ringlike members 17, 17', and these members must therefore be definitely fixed relative to the housing 7. This is accomplished by means of disklike members 21, 21' which secure the ringlike end members 17, 17' in proper positions and against axial displacement. Screws 22 hold the disks 21, 21' on the frame part 7.

The rotary parts of the switch, which are not shown in the drawings, extend between the recesses 23. These 50 rotary parts are provided on a casing connected with the frame 7 through the medium of fittings comprising the pins 24, 24' which determine the correct position thereof relative to the frame 7 and the bank contacts formed therein. These fittings are disposed in a median plane 55 of the switch, so that manufacturing tolerances can be dissipated in two directions.

Fig. 2 shows two fastening means for the bandlike conductors 1 on the insulating holder plate 2, which result from the displacement of the punching tool by 180°.

The manner in which the bare bandlike conductors are connected with the insulating holder plates is apparent from Figs. 3 and 4. It will be seen from Fig. 4, which shows a section through a bandlike conductor 1 at the side facing the wiring cable where it is folded upon itself, that the conductor is not abruptly folded about the edge of the auxiliary plates 25, 25', but is carried beyond such edge and then pressed together. The conductors are secured on the far or rear side facing the wiring cable, by bending over the ears 26, 26' about the auxiliary holder plates 25, 25'. The outwardly extending free end 27 is provided with a hole for receiving terminal means which may be soldered thereto.

In order to separate the multiple as may be desired, 75 it is only necessary to cut the folded edge 27 of the

conductor shown in Fig. 4 and to bend apart the two resulting conductor portions. The corresponding insulating holder plate 25, 25' separates the two conductor portions electrically.

We claim:

1. In an automatic telephone switching device having a frame, a plurality of holders comprising insulating mounting plates made of material subject to deformation responsive to atmospheric influences, said insulating mounting plates being arranged along an arc radially of the switch axis with the inner edges thereof spaced from such switch axis, each insulating mounting plate carrying a plurality of bare bandlike conductors folded thereabout to form along the corresponding inner edge a like plurality of bank contacts in fixed and intimate engagement with such inner edge, and a device for mounting said mounting plates to counteract deformation thereof responsive to atmospheric influences so as to secure said bank contacts in their assigned positions, said device comprising a first arcuate member fastened to said switch frame and engaging notches in said mounting plates approximately midway between the opposite ends thereof to fix said mounting plates axially of the switch, a plurality of second axially spaced arcuate members mounted on said frame, the convex edge of each arcuate member being serrated to form notches for interlocking engagement with notches formed along the inner edges of said mounting plates to fix the inner edges of such mounting plates in predetermined angular positions, a third arcuate member mounted on said switch frame in a median plane thereof and having serrations in its inner concave edge forming notches for receiving the rearward outer edges of said mounting plates so as to hold said outer edges in angularly spaced but radially outwardly displaceable positions, notches formed in the top and bottom edges of said insulating plates; an arcuate securing members having peripheral rims for interlocking engagement with said top and bottom notches to hold said insulating mounting plates against radial outward displacement but in axially outwardly displaceable positions.

2. In a bank multiple contact structure for axially successively disposed telephone switches or the like having flat insulating mounting plates for each switch which are disposed along an arc radially relative to the respective switch axis with the inner edges thereof facing such switch axis and carrying narrow continuous metallic bandlike conductors which extend from switch to switch and which are wound on said insulating mounting plates in flat helical convolutions to form inner portions which are bent about the inner edges of the respective insulating mounting plates in fixed engagement with such inner edges to form contacts which constitute the bank multiple contacts for such switch, a device for securing said insulating mounting plates to permit dimensional variations thereof due to temperature and moisture conditions to become effective substantially radially rearwardly in a direction away from the switch axis, said device comprising first retaining means for said insulating mounting plates for securing the inner edges of such plates in relatively fixed axial positions, second retaining means for securing the inner edges of said insulating mounting plates in assigned angular positions, third retaining means for securing the outer edges of said insulating mounting plates in assigned axial and angular positions while permitting radial displacement thereof, and fourth retaining means for securing the opposite ends of said insulating mounting plates against radial displacement while permitting axial displacement thereof.

3. The structure defined in claim 2, comprising an auxiliary insulating holder plate for each insulating mounting plate which is spaced therefrom radially rearwardly in a direction away from the switch axis, said metallic bandlike conductors being wound on said insulating mounting plate and its cooperating auxiliary holder plate.

4. The structure defined in claim 2, comprising means for anchoring each metallic bandlike conductor on said insulating mounting plate in back of the inner edge thereof of where such conductor forms a bank contact.

5. The structure defined in claim 2, comprising means for clamping each metallic bandlike conductor to said insulating mounting plate in back of the inner edge thereof of where such conductor forms a bank contact.

6. The structure defined in claim 3, comprising means for separately anchoring each metallic bandlike conductor on said auxiliary insulating holder plate and on said insulating mounting plate.

7. The structure defined in claim 2, wherein the portions of said metallic bandlike conductors wound about said insulating mounting plate which are disposed rearwardly in a direction radially away from the switch axis extend rearwardly radially spaced from the respective insulating mounting plate.

8. The structure defined in claim 2, wherein said first retaining means for securing the inner edges of said insulating mounting plates in relatively fixed axial positions is an arcuate member for engagement with notches provided in said mounting plates approximately midway of the opposite ends thereof.

9. The structure defined in claim 2, wherein said fourth retaining means comprises axially spaced members in engagement with the opposite ends of said insulating mounting plates for holding such plates against radial displacement.

10. The structure defined in claim 2, wherein said second retaining means for securing the angular positions of said insulating mounting plates at the inner edges thereof facing the switch axis comprises a plurality of arcuate axially spaced members in which are formed notches for interlocking engagement with notches formed along the inner edges of said insulating mounting members, and wherein said third retainer means for securing the angular positions of said insulating mounting plates at the outer edges thereof which face radially away from the switch axis is an arcuate member in which are formed notches for engagement by the outer edges of said insulating mounting plates.

11. In a bank multiple contact structure for axially successively disposed telephone switches or the like having flat insulating mounting plates for each switch which are disposed along an arc radially relative to the respective switch axis with the inner edges thereof facing such switch axis and carrying narrow continuous metallic bandlike conductors which extend from switch to switch and

50 which are wound on said insulating mounting plates in flat helical convolutions to form inner portions which are bent about the inner edges of the respective insulating mounting plates in fixed engagement with such inner edges to form contacts which constitute the bank multiple contacts for such switch, a device for securing said insulating mounting plates to permit dimensional variations thereof due to temperature and moisture conditions to become effective substantially radially rearwardly in a direction away from the switch axis, said device comprising first retaining means for securing said insulating mounting plates at a midpoint of the inner edges thereof in substantially fixed position while permitting limited play of the portions of said mounting plates extending from said midpoint toward the opposite ends thereof,

55 second retaining means for securing the inner edges of said mounting plates against radial play while permitting limited axial play thereof, and third retaining means for securing said mounting plates in their angular positions at the inner and outer edges thereof, said third retaining means permitting play of said mounting plates substantially only rearwardly in a direction away from the switch axis.

60 70 12. In a bank contact structure for telephone switches or the like having for each switch a plurality of flat elongated insulating plates made of material which is

subject to dimensional changes responsive to adverse atmospheric influences, each insulating plate carrying metallic contacts disposed along one edge thereof in fixed and intimate engagement with such edge and constituting bank contacts; a device for mounting the insulating plates associated with a switch angularly spaced along an arc with the contact-carrying edges thereof facing inwardly in radially spaced relation relative to the corresponding switch axis, said device comprising first retaining means for engagement with the contact-carrying inwardly facing edges of said insulating plates to secure the axial positions of said edges, second retaining means for engagement with said contact-carrying edges to secure the radial positions thereof at points intermediate the opposite ends of said insulating plates, and third retaining means for engagement with said insulating plates at the opposite ends thereof to secure the radial positions of said contact-carrying edges at the opposite ends of the corresponding insulating plates, said first and second and third retaining means cooperating to hold the contact-carrying radially inwardly facing edges of said insulating plates against harmful displacement incident to dimensional changes of the plate material responsive to adverse atmospheric influences so as to maintain said bank contacts in substantially predetermined positions relative to the switch axis.

13. In a bank contact structure for telephone switches or the like having for each switch a plurality of flat elongated insulating plates made of material which is subject to dimensional changes responsive to adverse atmospheric influences, each insulating plate carrying metallic narrow bandlike conductors folded thereabout to form along one edge thereof contacts in fixed and intimate engagement with such edge and constituting bank contacts, an auxiliary insulating strip made of similar material laterally spaced from the other edge of said in-
